FAUCET SPOUT HANDLE

William H. Armstrong, 5015 Brookdale,
Birmingham, Mich.

Filed Mar. 12, 1964, Ser. No. 78,971

Term of patent 14 years

(Cl. D91—3)

FIG. 1 is a perspective view of a faucet spout handle embodying my new design;

FIG. 2 is a top plan view thereof;

FIG. 3 is a side elevation view thereof; and

FIG. 4 is a front elevation view thereof.

The faucet spout, shown in broken lines, is included for illustrative purposes only.

I claim:

The ornamental design for a faucet spout handle, substantially as shown and described.
